(57) **CLAIM**

The ornamental design for a protective layer removal apparatus, as shown and described.

DESCRIPTION

FIG. 1 is a front elevation view of a protective layer removal apparatus embodying my new design;
FIG. 2 is a left side elevation view thereof;
FIG. 3 is a left side perspective view thereof;
FIG. 4 is a bottom perspective view thereof;
FIG. 5 is a top plan view thereof; and,
FIG. 6 is a bottom plan view thereof.

1 Claim, 6 Drawing Sheets
